UNITED STATES PATENT OFFICE.

MARTIN KLIMA, OF TABOR, WISCONSIN.

FEED-CUTTER.

SPECIFICATION forming part of Letters Patent No. 392,925, dated November 13, 1888.

Application filed June 8, 1888. Serial No. 270,507. (No model.)

To all whom it may concern:

Be it known that I, MARTIN KLIMA, of Tabor P. O., in the county of Racine, and in the State of Wisconsin, have invented certain new and useful Improvements in Feed-Cutters; and I do hereby declare that the following is a full, clear, and exact description thereof.

My invention relates to feed cutters, and will be fully described hereinafter.

10 In the drawings, Figure 1 is a plan view of my invention. Fig. 2 is a broken front elevation; Fig. 3, a section on line 3 3, Fig. 1; Fig. 4, a section on line 4 4, Fig. 2; and Figs. 5 and 6 are details.

15 A is the frame of my machine. B is the driving-shaft, and C the knife-wheel. The driving-shaft has its bearings at *a a'* and *a'* on the frame and lies parallel to the feed-box. It carries a bevel-pinion, E, just inside of its bearing *a'* to engage a bevel-wheel, F, which last has cast with it three or more pinions, *b c d*, each of less diameter than the other, in the order named, forming a nest, which is carried by a short shaft, G, which shaft may be cast 20 with said nest. The shaft G has its bearings in a cross-piece, *f*, at one end and in an arched strap, *g*, at the other.

H is the upper feed-roller shaft that is jointed at *h* and has a loose bearing at one 25 end in a bracket, I, that projects up from the cross-piece *j* of the frame, and just inside of its bearing carries a pinion, K, that meshes with a pinion, L, on the shaft M of the lower feed-roller. This last-named shaft is journaled 30 in each end of the frame, and is squared at *m* to receive the hub *n* of a pinion, N, which hub projects out on each side to receive the arms *O O'* of a bifurcated lever, P, and between the said arms a small pinion, *p*, is pivoted on an axle, *p'*. The handle of lever P extends forward, and is adapted for engaging 35 with either of the notches *q q' q''* of a standard, Q, that is bolted to the front portion of the frame.

40 The feed-rollers are formed with parallel rows of teeth *r*, which teeth are separated by alternately deep and shallow serrations, as at *s* and *s'*, respectively, as I find that surfaces formed in this way take hold of the stock bet-

ter than a surface made up of teeth separated by serrations of equal depth between all of the teeth.

The knives T are riveted or bolted to the flanges *c'* of the knife-wheel, and the blades are adjusted by set-bolts *c''* to give them the proper angle.

The shaft H passes through a stirrup, V, that hangs over the hood V' of the feed-box D, and a lever, W, that is hung to the frame at *w*, is linked to the lower member of the stirrup at *w'*, while the free end of lever W carries a weight, W', which weight is adjustable on the lever and serves through it to hold the upper roller down to its work.

The operation of my invention is as follows: 55 The squared portion of the shaft M is long enough to permit the pinion N to be adjusted thereon so as to bring said pinion and pinion *p* in line with either of the pinions *b c d*, and when these pinions are adjusted to give the proper speed to the rollers the lever P is depressed and its handle is caught under one of the notches *q q' q''* of the standard Q, where it is held down to secure the engagement of the pinion *p* with the proper pinion of the nest. 75

Having thus fully described my invention, what I claim as new, and desire to secure by Letters Patent, is—

In a feed-cutter, the combination, with the driving-shaft and its bevel-pinion, of a bevel-wheel and its shaft and a nest of pinions of varying diameters carried thereby, the feed-roller shafts and their pinions, a large pinion carried by the lower roller-shaft and adapted to slide thereon, the bifurcated lever with its arms on each side of the large pinion, and a small pinion pivoted between the arms of the lever for engagement with any desired pinion of the nest, substantially as described.

In testimony that I claim the foregoing I 90 have hereunto set my hand, at Milwaukee, in the county of Milwaukee and State of Wisconsin, in the presence of two witnesses.

MARTIN KLIMA.

Witnesses:

S. S. STOUT,
N. E. OLIPHANT.
